UNITED STATES PATENT OFFICE.

HENRY ABBOTT, OF EAST ORANGE, NEW JERSEY, ASSIGNOR TO THE CALCULAGRAPH COMPANY, A CORPORATION OF NEW JERSEY.

FASTENER FOR INK RIBBONS.

Application filed June 22, 1922. Serial No. 570,276.

To all whom it may concern:

Be it known that I, HENRY ABBOTT, a citizen of the United States, a resident of East Orange, in the county of Essex and 5 State of New Jersey, have invented a certain new and useful Improved Fastener for Ink Ribbons, of which the following is a specification.

The object of my invention has been to 10 provide a fastener for ink ribbons for use on time printing, typewriting and other machines, in which ink ribbons are used, which shall have, among other advantages, those of being efficient in operation, simple in application, and low cost of manufacture, and to such ends my invention consists in the fastener for ink ribbons hereinafter specified.

In the accompanying drawings—

20 Figure 1 is a perspective view of a ribbon fastener embodying my invention;

Fig. 2 is a similar view of a spool or spindle adapted to have such fastener applied thereto;

25 Fig. 3 is an end elevation of the said fastener applied to the said spindle and having a ribbon attached thereto.

In the fastening of an ink ribbon to a spool or spindle in printing machines using 30 such ribbons, there are several important or desirable considerations: the fastening should be easily applied to the spool, and this is not a simple matter, as the spool is usually in a more or less inaccessible position; the fastener should be one which will hold the ribbon securely, whether it be applied to the spool or fastened to the ribbon, so that it faces either toward or away from the body of the ribbon; the fastener should 35 also be readily so applied to the ribbon that it will cause the ribbon to wind truly on the spool and not obliquely. The fastener should also be such that the roll or winding of ribbon will be of as uniform diameter as 40 possible, especially where the change in size of the roll is to be used to control or operate an automatic reverse for the mechanism by which the ribbon is wound upon one spool or the other. The ribbon fastener which is 45 the subject of the present application, is the result of long experience in dealing with the foregoing difficulties and successfully complies with said conditions.

50 The illustrated embodiment is the best 55 form of my invention known to me, but my

invention is capable of embodiment in various forms, and the one chosen for illustration is, therefore, to be taken only as typical and my invention is not to be limited thereto.

The fastener shown in the accompanying drawings, comprises a body 1 which, in the present instance, is in the form of a strip of sheet metal, having a clip or clips 2 formed on or attached thereto, so that the fastener may be sprung on to a spool or 60 spindle 3 about which the ribbon is to be wound. The said body is provided with a flange or other form of shoulder 4 which is adapted to engage some form of shoulder on the spool, such as that formed by a groove 65 5 cut longitudinally in the spindle. The ink ribbon 6 is fastened to the body 1 in any convenient manner, and preferably by spurs or prongs 7 which are struck up out of the metal forming the said body. The ribbon 70 is impaled upon the spurs and the spurs are bent down upon the ribbon to secure it to the body. The spurs or other form of ribbon-fastening means, are located near the flange 4 or other form of shoulder on the 75 fastener for engaging the groove 5 or other form of shoulder on the spindle rather than at a distance from said flange, such as being formed upon the clips 2.

In the use of my fastener, the ribbon 80 having been so secured to the fastener as to be perpendicular to the flange and centrally located upon the body 1, the fastener is applied to the spool simply by placing the flange 4 in the groove 5 and springing the 85 clips 2 over the convexity on the opposite side of the spool.

The fastener which has just been described, cannot be applied to the spool in such a manner that it will not be secure. 90 If the ribbon-fastening spurs had been located on the opposite side of the spool from the flange, as by being formed on the clips 2, and the fastener were applied to the spool so that the pull of the ribbon would 95 be away from the open side of the fastener—that is, away from the gap between the ends of the clips and the flange, the pull of the ribbon could spring the clips back over the rounding of the spool and release 100 the fastener entirely. However, by locating the spurs or other form of ribbon fastening in proximity to the flange or other form of shoulder, the pull of the ribbon is applied 105 principally and almost wholly to the flange 110

and hardly at all to the clips, so that the fastener will hold the ribbon, no matter in which of the two possible directions it be wound upon the spool. My clip has very little thickness radially and, therefore, only to a slight extent changes the diameter and contour of the roll of ribbon. This enables the increase or decrease of the diameter of the roll to be efficiently used to operate a device for changing the direction of feed of the ribbon.

Having particularly described my invention, what I claim and desire to secure by Letters Patent is:

1. A ribbon fastener for spools comprising a body having a shoulder that is adapted to co-operate with a shoulder on a spool by a motion perpendicular to the axis of the spool, means for securing said body to the

spool, and means relatively close to said shoulder for securing the ribbon to said body and on the same side of said shoulder as said body.

2. A fastener for ribbons comprising a body having a flange that is adapted to engage a groove in a spool, means carried by said body that are adapted to be sprung over the convexity of the spool to secure the fastener to the spool, and means adapted to secure a ribbon to the fastener, said last mentioned means being located upon the same side of said shoulder as said first mentioned means.

In testimony that I claim the foregoing, I have hereunto set my hand this 13 day 35 of June, 1922.

HENRY ABBOTT.
